UNITED STATES PATENT OFFICE

GEORGE GERARD DUEARING, OF FORT BLISS, TEXAS

AIRSHIP

Application filed September 12, 1930. Serial No. 481,484.

The present invention relates generally to the art of aerial navigation and more particularly to a new and novel form of dirigible airship, the principal object of the invention being to generally improve upon and simplify the construction of the existing types of airships so that a relatively larger airship may be provided than that now in use.

10 A further object of my invention is to provide an airship having a pair of elongated cylindrical like bodies arranged substantially parallel with each other, each body being adapted to receive a lighter than air 15 gas and to arrange between said bodies an elongated cabin structure which cooperates with the cylindrical bodies in forming a sustaining plane which is effective in materially increasing the lifting and carrying capacity 20 of the airship.

A still further very important object of the invention resides in the provision of an airship of this nature which has its parts arranged in a convenient compact manner 25 capable of withstanding storms and inclement weather and is thoroughly efficient in use and operation.

With the above and numerous other objects in view as will appear as the description proceeds, the invention resides in certain novel 30 features of construction, and in the combination and arrangement of parts as will be hereinafter more fully described and claimed.

In the drawings: 35 Figure 1 is a bottom plan view of an airship embodying the features of my invention,

Figure 2 is a longitudinal section through the cabinet taken substantially on the line 40 2—2 of Figure 1,

Figure 3 is an end elevation thereof,

Figure 4 is an enlarged detail section showing the arrangement of the motors and propellers, and

45 Figure 5 is a transverse sectional view taken substantially on the line 5—5 of Figure 1.

Referring to the drawings in detail it will be seen that the numeral 5 denotes a stream 50 line cabinet having a plurality of floors 6

formed therein to provide different storage for different purposes. On the bottom of the cabinet there are provided doors 7 for the loading and unloading of the cabinet.

Laterally extending tubes 8 extend from 55 the sides of the cabinet and are connected with cylindrical like bags or bodies 9 for containing lighter than air gas. These bodies may be constructed in stream line fashion in the usual well known manner having conventional rudders and elevators on the rear ends thereof.

On the bottoms of the bodies 9 are ground 60 engaging bumpers 10. On the lower outer sides of the bodies there are arranged motor 65 housings 11 and motors for operating propellers 12. These propellers are arranged at the front and rear of the group of housings and between the housings. Enclosed windowed gangways 14 are provided over these 70 housings to provide ready access to the engines by the crew. It will be seen that the crew may pass from the cabinet through the tubes 8 into the bodies and into the gangways 75 14 with ease and facility.

It is thought that the construction, operation, utility and advantages of this invention will now be quite apparent to those skilled 80 in this art without a more detailed description thereof.

The present embodiment of the invention, of course, has been described in considerable detail merely for the purposes of exemplification since in actual practice it attains the 85 features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what 95 I claim as new is:

1. In an airship of the class described, a cabinet, a pair of lighter than air gas containing bodies one to each side of the cabinet and means connecting the bodies to the cabinet, said means being in the form of hol- 100

low tubes to provide means for entering the bodies from the cabinet and vice versa.

2. In an airship of the class described, a cabinet, a pair of lighter than air gas containing bodies one to each side of the cabinet and means connecting the bodies to the cabinet, said means being in the form of hollow tubes to provide means for entering the bodies from the cabinet and vice versa, motor housings on the lower outer sides of the bodies arranged in groups disposed longitudinally, and propellers at the front and rear of the groups and between the housings.

3. In an airship of the class described, a cabinet, a pair of lighter than air gas containing bodies one to each side of the cabinet and means connecting the bodies to the cabinet, said means being in the form of hollow tubes to provide means for entering the bodies from the cabinet and vice versa, motor housings on the lower outer sides of the bodies arranged in groups disposed longitudinally, and propellers at the front and rear of the groups and between the housings, and closed gangways over the housings to permit ready access thereto and movement from one housing to the other.

In testimony whereof I affix my signature.

GEORGE GERARD DUERING.
